CLIFFORD T. SWITZLER, OF NEWTON, MASSACHUSETTS, ASSIGNOR TO REELY-TROOLY CO., OF BOSTON, MASSACHUSETTS, A CORPORATION OF MASSACHUSETTS.

CUT-OUT DOLL.

1,150,792.

Specification of Letters Patent. Patented Aug. 17, 1915.

Application filed February 5, 1915. Serial No. 6,251.

To all whom it may concern:

Be it known that I, CLIFFORD T. SWITZLER, a citizen of the United States, residing at Newton, county of Middlesex, State of Massachusetts, have invented an Improvement 5 in Cut-Out Dolls, of which the following description, in connection with the accompanying drawing, is a specification, like characters on the drawing representing like parts.

This invention relates to dolls of the cut-out variety, that is, dolls which are printed either completely or in outline on sheet material and are intended to be cut out by the 10 person playing with them. The cut-out dolls which are now commonly used have the doll outline printed on paper, and this outline usually has imprinted upon it the features of the head and also representations 15 of the hands and feet. The body portion of 20 the doll is, however, generally left blank and to complete the doll necessitates either coloring the body portion to simulate a dress, or applying to the body portion a 25 separate piece of paper having the representation of a dress thereon. In either case 30 the representation of the dress is imperfect because real dresses are made of cloth and it is difficult to so color the paper as to produce a realistic simulation of a dress.

I have by my invention aimed to provide a novel cut-out doll in which the portion 35 thereof representing a dress is made of cloth and thus simulates a cloth dress, while the portions representing the hands, feet, head 40 and other parts not covered by the dress are presented by paper or other material properly imprinted by which a fairly correct imitation in coloring can be obtained.

I produce my improved doll by cutting 45 out from a piece of cloth a doll outline having the shape of the completed doll and then applying a facing layer to all portions of the cut-out piece of cloth except such portions as represent the dress of the completed 50 doll, which facing layer is imprinted to represent the head, arms, legs, etc. In this way a cut-out doll is produced in which the head, arms, legs and other portions of the body 55 not covered by the dress have the same appearance as that of an ordinary paper doll, and in which the portion thereof representing the dress is made of cloth and can be so cut from the cloth that the pattern of the cloth will appear in the doll in a manner

similar to that in which it would appear in a dress actually made from the cloth. The cut-out doll is, therefore, much more realistic than the ordinary paper doll, and it has the further advantage that the cloth body is 60 much stronger than the paper from which the ordinary paper doll is made, thus, making my improved doll practically indestructible. Moreover, since the body portion of the doll is made of cloth, it can be 65 bent so as to allow the doll to assume different postures without danger of breaking or cracking the doll, as frequently happens when paper dolls are being played with.

In order to give an understanding of my 70 invention I have illustrated in the drawings a selected embodiment thereof which will now be described, after which the novel features will be pointed out in the appended 75 claim.

In the drawings, Figure 1 indicates a completed doll embodying my invention; Fig. 2 shows the piece of cloth with the doll outlines thereon and which are to be cut therefrom; Fig. 3 shows a sheet of paper or 80 similar material having imprinted thereon outlines and representations of the portions of the doll not covered by the dress, such, for instance, as the head, hands, feet, etc. Fig. 4 is a section on the line $x-x$, Fig. 1. 85

I have shown at 1 a sheet of cloth on which are printed the outlines 2 of one or more dolls, said outlines being those of a doll fully dressed. If the cloth 1 has a pattern, the outlines 2 will be so positioned 90 thereon that the stripe or other pattern of the cloth will have the same position in the outline as it would have if the same cloth were made into a regular dress.

I have shown at 3 a sheet of paper or other similar material on which are printed the outlines of the portions of the doll which are not to be covered by the dress in the completed doll. In the illustrated embodiment of my invention these outlines are the outline of the head 4, the outline of the hands and lower arms 5, 6, the outlines of the feet and the portions of the legs exposed below the dress, as shown at 7 and 8. The outline 4 of the head will preferably be printed to indicate the features of the face and represent the hair, etc., and if desired the head may be colored to indicate the flesh tints. Similarly the hands and feet sections 5, 6, 7 and 8 may be printed to in- 100 105 110

dicate in more or less detail these members of the body and may be printed in any desired colors. The feet portions 7 and 8 may be printed to indicate shoes, stockings, or any other foot covering. The outline of the head 4 is a duplicate in shape of that of the head portion of the doll outline 2, and the hand and feet portions 5, 6, 7 and 8 are also exact duplicates in shape with the corresponding portions of the doll outline 2.

10 In making the doll the child will first cut out the doll outline 2 from the cloth, and will then cut out the head, hands and feet outlines 4, 5, 6, 7 and 8. When this is done, the head 4 will be pasted or permanently secured to the head portion of the doll outline 2, the hands and feet portions 5, 6, 7 and 8 will also be pasted or otherwise permanently secured to the corresponding portions of the doll cut-out 2. This completes the doll and produces the very realistic doll shown in Fig. 1. Such doll has all the portion thereof constituting the dress made from cloth, while the portions representing the parts of the doll not covered by the dress are represented by the paper parts 4, 5, 6, 7 and 8 that can be readily printed to present a very perfect imitation of the corresponding parts of a human figure. Since 30 the body of the doll is formed of cloth, it can be easily bent or folded without danger of breaking. The head, arms, and feet and

other parts not covered by the dress are comparatively stiff by reason of the fact that they are formed not only by the cloth backing, but by the paper facing layer having the representation of the exposed parts of the body thereon. The cloth backing stiffens the paper facing layer so that it will not crack or tear, thus making a very strong 40 and practically indestructible doll.

35 A doll embodying my invention is much more attractive to the ordinary child than a paper doll because the dress portion of the doll is made of cloth, thus producing a much more realistic doll than it is possible to produce with paper alone.

45 I claim:

A cut-out doll comprising a body portion of cloth having an exterior contour similar 50 to that of the completed doll and a facing layer permanently secured to and covering all portions of the cloth body except that representing the dress of the doll, said facing layer being imprinted to present a like- 55 ness of the portions of the doll not covered by the dress.

In testimony whereof, I have signed my name to this specification, in the presence of two subscribing witnesses.

CLIFFORD T. SWITZLER.
